SUPERHEATER HEADER

William Ernest English, Bishopston, Swansea,
Wales, assignor to The Superheater Company,
New York, N. Y., a corporation of Delaware

Application May 22, 1930, Serial No. 454,770
In Great Britain May 25, 1929

3 Claims. (Cl. 122—462)

This invention relates to superheater headers for example as used in locomotive boilers but which may be also employed in other types of boilers and having longitudinal saturated and 5 superheated steam passageways or conduits running more or less in parallel with separate branched-off chambers which may be positioned side by side alternately along the conduits and to which the opposite ends of the tube elements are 10 connected.

Constructions such as above indicated have generally been formed as castings often in one piece but the high pressures say up to some 950 lbs. per square inch now contemplated in steam 15 boilers with corresponding temperatures of say 750° F. or thereabouts together with the temperature differences set up by the varying heat-absorbing capacities of wet and dry steam render the making of satisfactory castings a complicated 20 and difficult process and it may at times be practically impossible to obtain castings suitable for such apparatus.

The object of the present invention is to overcome objections such as the foregoing and to provide 25 for the construction of an improved superheater header from material capable of withstanding a high degree of stress.

The invention consists in a superheater header of the kind indicated which is formed throughout from wrought steel components suitably connected together.

The invention further consists in a superheater header having one or more steel longitudinal components with saturated and superheated 35 steam conduits provided in parallel therein and a series of chambers formed separately from steel connected to and branched off alternately from said conduits.

The invention further consists in a superheater 40 header formed of a drawn steel or like tubular longitudinal component suitably divided to provide saturated and superheated steam conduits side by side and having a series of steel branched-off chambers connected alternately with said conduits and to which the tube elements are attached.

The invention further consists in a superheater header in accordance with the preceding paragraph in which a rectangular drawn or 45 otherwise formed steel tubular component having a series of circular apertures along one of its broadest sides is divided to provide saturated and superheated steam compartments by a longitudinal partition disposed, and welded in, generally in a plane containing the axes of said

apertures and waved or deformed oppositely at alternate apertures to effect a junction with a part of the perimeter of each aperture and with the intervening strips of wall which may constitute tangents thereto.

The invention further consists in a steel superheater header as indicated in which a longitudinal component is constructed from a suitable ingot having saturated and superheated steam conduits formed in parallel therein as by drilling 60 while recesses are formed in a line in an outer side in the material adjacent to both conduits for the connection of steel branched-off chambers which communicate alternately with said saturated and superheated conduits by holes drilled 65 or otherwise formed at suitable angles from said recesses.

The invention further consists in a steel superheater header having separate longitudinal saturated and superheated conduit components 70 in spaced relationship and a series of steel transverse branched-off chambers to which the tube elements are attached extending between said components and connected to conduits of one or the other alternately.

The invention further consists in a superheater header in accordance with the preceding paragraph and having a pair of drawn steel conduit components with suitably closed ends positioned in spaced relationship by a series of transverse 75 chamber components each with an open end connected by screwing, expanding or otherwise alternately to one or other conduit and with their other ends closed and attached where desirable to the exterior surface of the other conduit component.

The invention further consists in a steel superheater header having longitudinal saturated and superheated steam conduits formed from wrought 80 material as separate components with a series of forged transverse branched-off chamber components suitably fastened to the longitudinal components in such a manner that each alternate chamber connects to one conduit while the remaining chambers connect to the other conduit. 85

The invention further consists in a superheater header in accordance with the preceding paragraph having solid drawn hollow rectangular cross section longitudinal saturated and superheated steam conduit components arranged side 90 by side with the transverse chamber components fastened to the undersides thereof.

The invention further consists in a superheater header in accordance with the paragraph next but one preceding having solid drawn longitudi- 100

nal saturated and superheated steam conduit components arranged one above the other and each having in section the form of a rectangle with a corner adjacent to the other rectangle 5 heavily chamfered so that the walls of the chamfered regions stand adjacent and more or less normal to each other and are provided with apertures into which the alternately oppositely angled branches of a series of parallel branched-off 10 chamber components are fastened.

The invention further consists in a superheater header in accordance with any of the preceding paragraphs in which the transverse chamber components are formed as solid forgings having 15 a flat lower surface projecting on each side from an upper half round body part provided at an end with a branch or boss screwed externally for making a connection to the longitudinal conduits and the solid material is bored to form the in- 20 ternal chamber.

The invention further consists in a superheater header in accordance with the preceding paragraph in which the lower surface of the transverse chamber components is provided with a 25 series of pairs of apertures for reception of the ends of the tube elements, said apertures by drilling at opposite inclinations being made to diverge as they proceed outward from the chamber and being shaped at their outer ends to facilitate con- 30 nection of the tube element ends.

The invention further consists in a superheater header in accordance with any one or more of the preceding paragraphs in which slots or spaces are provided between the projecting edges of the 35 lower faces of adjacent transverse chamber components for accommodating bolts for connecting the superheater tube elements and in order to reduce the length and prevent rotation of said bolts recesses may be formed in the projecting edges 40 for the bolt heads.

The invention also consists in the improved steel superheater headers having branched-off chambers as indicated in the following description.

Referring now to the accompanying drawings:—

Figures 1 and 2 are an elevation and a plan respectively of a superheater header in accordance with the invention;

Figures 3 and 4 are end views partly in section, and

Figure 5 is a view of the partition or diaphragm of the same header;

Figure 6 is a section to an enlarged scale 55 through two of the transverse chamber components, and

Figure 7 is a longitudinal section of a component shown in position in a header of a varied form;

Figures 8 and 9 show an elevation and a plan respectively of a header of the kind shown in section in Figure 7.

In carrying the invention into effect in one convenient form shown in Figures 1, 2, 3, 4 and 65 5 a drawn steel rectangular tubular member a say of $9\frac{1}{2}''$ by $5''$ internal dimensions and $1\frac{1}{8}''$ thick is made of a length sufficient to allow for closing of the ends as hereinafter described and is provided along the centre of one of its broader 70 sides with a series of say eight or other desirable number of circular apertures b of a suitable size to be provided with internal screw threads for the reception of screwthreaded members of say $4\frac{1}{4}''$ external diameter as herein- 75 after described.

The internal capacity of the tubular member a is divided into saturated and superheated steam compartments by inserting a diaphragm or partition c formed from a strip of material of say $\frac{1}{2}''$ thick, the material being originally flat and remaining substantially so along one edge but being waved upon the other edge alternately upwards and downwards as shown at c' , c^2 so that when the piece is inserted longitudinally in the tubular member a the waved edge of the partition plate c will follow about one-quarter of the top or bottom of the perimeter of the apertures b .

This partition plate c is made of sufficient width so that after waving its edges may be planed level and in two parallel planes so that the plate will abut closely against the sides of the two opposite walls of the tubular member a , the one side following a straight line down the centre of the tube, with the exception of a depression c^3 for an enlarged aperture hereinafter described and the other side following first the top and then the bottom of alternate apertures b and abutting against the wall between the apertures along a strip c^4 inclined so as to form tangents to the curved abutting portions c , c^2 .

A small depression c^3 is made in the centre of the length of the partition plate on the opposite edge to the waves c' , c^2 to clear a $6''$ diameter tapping hole formed in the wall of the upper longitudinal compartment, said hole being positioned as close as possible to the upper side of the compartment and necessitating a deflection of the partition by some $1\frac{1}{2}''$ at this point.

The two ends of the partition plate c are 110 differently formed, as at one end shown at c^5 the full width of the plate rises in an inclined direction from following rather more than one-quarter of the perimeter of the second aperture up to the top of the tubular member. From this 115 end c^5 one edge is waved downward at the second, fourth, sixth and eighth apertures as shown at c' and upwards at the third, fifth and seventh apertures as shown at c^2 . From the wave below the eighth aperture the full width of the plate 120 is bent upwards and somewhat backwards as shown at c^6 so that the edge of the plate follows about one-half or rather more of the perimeter of the eighth aperture.

When in position as indicated and before any 125 closing of the end of the tubular member a takes place, the partition plate c is welded along the whole of the length of both of its edges and at both ends to the walls of the tubular member a with which it is in contact.

The welding is effected by an acetylene blow pipe or electric welding or other process for example through the apertures in the wall of the tube, the welding being carried at each aperture round the periphery and up to the line of the 130 centre of the apertures. At the line of the centre of the apertures the welding is carried right through to the other side of the plate and then it is picked up on the other side through the next aperture and carried round another half 140 and so on until the turned-up end portions of the plate are reached, these regions being easily accessible through the unclosed ends of the tubular member a . Upon the edge of the plate c remote from the apertures the welding is similarly effected through the apertures in the opposite side, a length equivalent to the distance apart of the apertures being welded at one aperture on one side of the plate and a similar operation performed from the next aperture on the 145 150

other side of the plate, the welding being carried across at the junction as already described in connection with the welding of the waved edge. The depressed central portion c^3 of the 5 normally straight edge of the plate is treated as the rest.

The eight apertures b may be positioned at say 6 $\frac{1}{8}$ " apart and in the bottom narrow side of the member a there is formed at each end a 10 screw-threaded hole b^2 of say 5" external diameter for the reception of the externally screwed branches d for the outlet of the superheated steam, the central hole b' at the top of the centre of the tubular member a being for 15 the saturated steam and being also fitted with a suitable branch e . This branch may be formed from a short length of 6" external diameter 1/2" thick tube with a suitable diameter flange formed integral therewith, the end of the tube being 20 screwed into the central aperture of the tubular member and welded externally. For the superheated steam outlets the branches d are formed as tubular elbows having say rectangular flanges for 4 $\frac{1}{2}$ " internal diameter pipe at their ends so 25 disposed as to be level with the front of the tubular member when the branches are screwed up. These branches d may also be welded externally after being screwed in.

The tubular member a may have an overall 30 length of some 5 feet and the ends may be curved away from the upper to the lower side for example as shown to follow the interior of a locomotive smoke box within which the superheater may be fixed. The closing of these 35 ends may be effected in any desired way as for example by the insertion of separate pieces and welding over of the material of the edge of the walls of the tubular member to form a pressure-tight junction therewith.

40 The branched-off chamber components f shown enlarged in Figures 6 and 7 and in connection with a modified tubular member in the latter view are fitted to the apertures b in the front wall of the tubular member a and form connecting means for the tubular elements of the superheater.

In one form these chambers may be made from solid steel drilled out and may be conveniently stamped from a bar having a cross section which 50 provides a D-shaped upper part with a somewhat wider or flanged lower portion g . The flanged lower portion g may have a width say of 5 $\frac{1}{4}$ " with a thickness of 1 $\frac{1}{4}$ " and the D-shaped upper part may have a semicircular back of say 55 3 $\frac{3}{4}$ " diameter with a parallel intervening portion of some $\frac{7}{8}$ " between the centre of the semicircle and the back of the flanged part. The overall length of each of these chamber components f may be about 9 $\frac{5}{8}$ " and they may be 60 conveniently drilled or bored lengthwise with say 2 $\frac{3}{4}$ " diameter holes to within a short distance of the closed end, the axis of the bore corresponding with the centre of the semicircular back so as to leave the metal about $\frac{1}{2}$ " thick round 65 the rounded side of the component and about $\frac{3}{4}$ " thick in the centre of the flanged side. At the open end the flanged side will be cut away for a length of say 1 $\frac{1}{2}$ " to form a circular end h of say 4 $\frac{1}{4}$ " diameter which will be screw threaded externally for connection to the tapped apertures b of the header component, the chamber components being spaced 6 $\frac{1}{8}$ " centres along the header and having the flanged sides of 5 $\frac{1}{4}$ " wide will provide intervening spaces of 1 $\frac{1}{8}$ " wide in 70 which bolts may be inserted for attaching the

tubular elements to the chambers by means of clips of any known or convenient form.

The underside flat faces of the flanged lower portion g of the transverse chamber components f are provided with apertures i for the reception of the ends of the superheater tube elements, these apertures being formed by drilling at opposite inclination holes arranged in pairs transversely of the axis of the chamber components, each chamber with certain exceptions where necessary being conveniently provided with three pairs of holes, one pair situated at the centre and the other two pairs being each adjacent to one of the ends.

80 The holes i of each pair are drilled at an inclination to one another in order to enter the bored chamber of the component and at the same time to be spread far enough apart on the surface to permit of the connection of the tube elements. Countersunk or other recesses 85 are formed around the holes to provide suitable seating surfaces for the ends of the tube elements.

A known form of connection for the tube elements may comprise a dog j embracing the two 100 tubes l of an element and provided with a central aperture through which a bolt k is inserted to pull the tube ends into the recesses of the holes i by means of the dog j .

A dust cover or shield piece m abutting against 105 the face of the apertures on the header component a and extending over the top and front of the chamber components f may be provided for protecting the nuts and bolt ends when in use.

110 In another form of the invention shown in Figures 8 and 9 and enlarged at Figure 7 the tubular member or component may be formed from a solid forging or ingot a' of the required length and external dimensions, there being 115 provided as for example by drilling two parallel channels or passageways a^2, a^3 running from one end to the other of the member a' and providing the separate compartments for saturated and superheated steam.

120 The exterior may be shaped in any desired manner for example with rounded edges a^4 to reduce the thickness of material at the corners and with a thickened band a^5 to provide deeper recesses for screw-threaded connections.

125 Along the band a^5 of the member a' so formed there is drilled a series of holes or recesses b^3 which may be 6 $\frac{1}{8}$ " apart and screw threaded to receive branched-off chambers f of a kind similar to those already described, the recesses 130 being made of such a depth that sufficient material is left between the edge of the recess b^3 upon each side and the bores of the two conduits a^2, a^3 in the member. Holes b^4 or b^5 are then drilled from each of the recesses into one 135 or other of the conduits alternately and the connection of the branched-off chambers f with the conduits is thus effected. A hole b^6 is also made in the upper conduit a^2 at or about the middle of its length for the insertion of a saturated 140 steam branch e and at each end of the lower conduit holes b^7 are provided for the insertion of superheated steam outlet branches d' all more or less as hereinbefore described in connection with the other construction. The ends of the 145 drilled conduits may finally be closed in any desirable or convenient manner as for example by means of screwed plugs or other devices.

If desired an ingot or forging of rectangular cross section and suitable dimensions may be used 150

instead of the form last described for the drilled tubular header member or component.

It is to be understood that the constructions hereinbefore described are given by way of example only and that modifications and additions may be introduced without departing from the nature of the invention as set forth in the foregoing statements.

Having now described my invention, what I claim as new and desire to secure by Letters Patent is:—

1. A superheater header comprising a component formed to withstand internal pressures of 1000 lbs. per square inch and upward, and having a series of apertures through one of its walls in a line parallel to the length of the header, and divided to provide saturated and superheated steam compartments by a longitudinal partition disposed generally in a plane with said apertures, 15 passages being provided sloping alternately upward and downward putting said apertures into communication alternately with said two compartments, and branched-off chambers fixed to said header so as to communicate with said apertures.

2. A superheater header comprising a rectangular tubular component formed to withstand

more than 1000 lbs. pressure per square inch and having a series of circular apertures along one of its broadest walls and divided to provide saturated and superheated steam compartments by a longitudinal partition disposed generally in a plane containing the axes of said apertures and deformed oppositely at alternate apertures to effect a junction with a part of the perimeter of each aperture and with the regions of wall constituting tangents to the perimeters of apertures and a series of steel branched-off chambers formed independently and connected alternately with said conduits and to which the tube elements are attached.

3. A steel superheater header formed to withstand about 1000 lbs. pressure per square inch and comprising a longitudinal component constructed from a suitable ingot having parallel drilled saturated and superheated steam conduits, recesses disposed in a line in an outer side in the material adjacent to both conduits, a series of steel branched-off chambers fixed in said recesses and holes drilled at suitable angles from said recesses which communicate alternately with said saturated and superheated conduits.
